ATTORNEY

UNITED STATES PATENT OFFICE.

CHRISTIAN B. BACKER, OF BROOKLYN, NEW YORK.

CONCENTRIC HOT PLATE.

Application filed October 20, 1927, Serial No. 227,445, and in Great Britain January 28, 1927.

My invention relates to electrically heated devices and particularly to electric-heating units.

An object of my invention is to provide a relatively simple, highly efficient, flat electric-heating unit, the surface of which shall be uniformly heated.

Another object of my invention is to provide a two-part heater that shall embody means for maintaining the two parts in proper operative positions relatively to each other and for reducing the heat flow therebetween.

In practicing my invention, I provide an inner heating unit embodying a plurality of metal-encased tubular heating elements embedded in a substantially circular mass of cast metal having a peripheral shoulder thereon and an outer annular heating unit embodying a plurality of metal-encased tubular elements embedded in an annulus of cast metal. A screw-threaded stud extends into the central mass of cast metal and cooperates with a metal spider to hold the two units in proper operative position in one plane.

In the single sheet of drawings:

Figure 1 is a view, in section on the line I—I of Fig. 2, of a device embodying my invention, and

Fig. 2 is a top plan view thereof.

A two-part heater embodies an inner heating unit 11 and an outer heating unit 12, the two parts being concentrically located.

The heating unit 11 embodies a pair of metal-encased tubular heating elements 13 and 14, each bent to substantially U-shape, as is shown more particularly in Fig. 2 of the drawing, and located in a single plane, the end portions thereof being bent downwardly out of the plane of the other part of the heating elements.

Each of the heating units 13 and 14 embodies an outer metal casing 15, a helix 16 of resistor wire located therein and held tightly by a crystalline mass 17 of electric-insulating material consisting of magnesium hydroxide or oxide. The method of making these heating elements is more particularly disclosed and claimed in my Reissue Patent No. 16,340.

Briefly, the method therein described comprises winding a resistor wire into helical

form, surrounding the helix of resistor wire with an open helix of metallic magnesium, preferably in strip form, and then locating the two helices within an outer metal casing, such as the tube 15. The entire assembly is then subjected, for a predetermined length of time, to the action of high-temperature steam or water, under pressure. The initially metallic magnesium is thereby transformed into magnesium hydroxide or oxide, the volume occupied thereby increasing to substantially twice that occupied by the metallic magnesium. The result is that the mass of electric-insulating material tightly grips or holds the resistor helix within the metal tube, which tube may then be bent to any desired shape, such as that shown in the drawings. As the mass 17 of magnesium hydroxide or oxide, is a crystalline mass that provides a heat-conducting path from the resistor to the metal tube, of very low thermal resistance, so that there is a relatively small temperature gradient only between the resistor and the outer surface of the metal tube.

The two heating elements 13 and 14 are then located in a suitable mold and held by molding nails or other suitable means, to permit of casting therearound a mass 18 of metal which is preferably made flat and circular. A peripheral shoulder portion 19 is provided at the upper edge thereof, and the upper surface thereof is smoothed and polished, as may be considered necessary or desirable.

The outer annular heating element 12 embodies a plurality of metal-encased tubular heating elements 21 and 22 which are bent to substantially circular shape and which are located in the same plane. The end portions thereof extend downwardly out of this plane. The method of construction of the heating elements 21 and 22 is the same as has been hereinbefore described for the heating elements 13 and 14.

An annulus 23 of cast metal is provided to embed the heating units 21 and 22, the method of supporting the heating elements 21 and 22 during the casting operation being well known and, therefore, unnecessary to describe in detail.

The annulus 23 is provided with a plurality of peripherally spaced lugs 24 extending radially inward and located a slight distance

below the upper surface of the annulus 23. The inner faces of the lugs 24 are adapted to engage the outer peripheral surface of the circular mass 18 to cast metal, and the upper surface of the lugs 24 is adapted to fit below the shoulder portion 19 of the mass 18 of cast metal.

A screw threaded rod or stud 25 is located coaxially with the two heating units and more particularly with the masses of cast metal, a screw threaded opening being provided in the member 18 to receive the upper end of the stud. A spider or skeleton frame 26 is provided, having a central portion and a plurality of arms extending radially outward therefrom. The central portion has the stud 25 extending therethrough, and the outer ends of the arms operatively engage a portion of the lower surface of the annulus 12, being pressed thereagainst by a nut 27 having screw threaded engagement on the stud 25 and pressing against the central portion of the member 26. In order to reduce the heat flow from the mass 23 of cast metal to the spider 26, I prefer to cast the member 23 with a recess 28 in its lower surface, providing relatively narrow ridges of metal at the edge thereof, whereby the area of surface in actual engagement is reduced to a minimum.

The heating elements 13, 14, 21 and 22 hereinbefore described, are substantially standard articles and I have therefore, not described any additional details of construction, such as the terminals and the terminal construction provided therefor.

As has been hereinbefore stated, the two heating elements 13 and 14 in the central member 11 are each bent to substantially U-shape and are then located in such position that they extend oppositely to each other, as is shown more particularly in Fig. 2 of the drawing. This location permits of obtaining a substantially uniform temperature of the entire upper surface of the central heating unit, irrespective of whether the two heating elements 13 and 14 are connected in series-circuit relation and energized from a source of electric energy of a predetermined voltage to provide a low heat; whether only one of the heating elements is energized, or whether both heating elements are energized while connected in parallel-circuit relation. Such connections and method of control are well known in the art and it is, therefore, considered unnecessary to describe these in greater detail.

When it is desired to thus connect two heating elements in different relations to provide a selective plurality of temperatures, it is desirable, if not necessary, that the lengths of the resistor be the same, and the construction, shape and location of the heating elements 13 and 14 are such as to effect the desired result; namely, uniform heating of the operative surface of the unit 11 under all conditions of operation.

It is possible also to make the lengths of the heating elements 21 and 22 the same, so that they also may be connected in a plurality of relations, in the manner described above.

It is, of course, obvious that it is possible to energize the heating elements 13 and 14 either individually or simultaneously without, at the same time, energizing the heating elements 21 and 22. This permits of adapting the heater to the size of the cooking utensil being employed at any time.

The cooperating shoulder and lugs on the inner and the outer heating units provide a very simple means, which in combination with the spider and screw threaded stud, will maintain the two heating units in proper operative positions relatively to each other in both a radial plane and in a plane parallel to the operating surface of the heater. Simultaneously, the relatively small surface area of contact between the two heating units and, more particularly between the masses of cast metal, tends to reduce the flow of heat therebetween to a minimum.

Various modifications may be made in the device embodying my invention without departing from the spirit and scope thereof, and I desire, therefore, that only such limitations shall be placed thereon as are imposed by the prior art or are specifically set forth in the appended claims.

I claim as my invention:

1. A multi-unit heater comprising a central circular mass of cast metal having an outer overhanging shoulder portion and a metal-enclosed tubular heating element embedded in the cast metal, and an outer annular mass of cast metal embodying a plurality of inwardly-extending lugs fitting below said shoulder portion to locate the annular mass in proper operative position both axially and radially relatively to the central mass, and a metal-enclosed tubular heating element embedded in said annular mass.

2. An electric heater comprising a central substantially circular mass of cast metal embodying an outer peripheral shoulder adjacent to the upper surface thereof, a metal-enclosed tubular heating element embedded in said mass, an outer annular mass of cast metal embodying a plurality of inwardly projecting lugs fitting below said shoulder, a metal-enclosed tubular heating element embedded in said annular mass of cast metal, a screw-threaded rod having its upper end extending into the central mass of metal, a skeleton frame of substantially T-shape, the inner portion of which fits over the rod and the outer ends of which operatively engage the annular mass of metal, and a nut on said rod for holding the skeleton frame in close operative engagement with the annular mass of metal, the lugs of which are thereby pressed against the shoulder on the central mass of metal.

3. An electric heater comprising a central

circular unit and an outer annular unit, each unit embodying a metal-encased tubular heating element, and a mass of cast metal embedding the same, and the annular unit having a plurality of lugs integral with the cast metal and extending radially inwardly to engage the circular unit to space the heating

units apart and reduce heat flow therebetween.

In testimony whereof, I have hereunto subscribed my name this 10th day of October, 1927.

CHRISTIAN B. BACKER.
